F. A. Richards.

UNITED STATES PATENT OFFICE.

EDWARD E. TRYON, OF EAST HARTFORD, CONNECTICUT.

BICYCLE-LOCK.

SPECIFICATION forming part of Letters Patent No. 601,290, dated March 29, 1898.

Application filed October 11, 1897. Serial No. 654,815. (No model.)

To all whom it may concern:

Be it known that I, EDWARD E. TRYON, a citizen of the United States, residing in East Hartford, in the county of Hartford and State 5 of Connecticut, have invented certain new and useful Improvements in Bicycle-Locks, of which the following is a specification.

This invention relates to improvements in bicycle-locks; and it has for its object the 10 provision of a simple device of this character so constructed as to lock the steering-head of a bicycle securely to the steering-tube, said lock consisting of a minimum number of parts which can be quickly assembled in working 15 position on the steering-head tube.

The main feature of my invention resides, in connection with a steering-head and a tube, in a locking-bolt carrier having screw-receiving openings, a series of screws passing 20 through said openings and in threaded engagement with the steering-head tube, a casting fitting around said carrier, and a bolt passing through a bore in a carrier and adapted to be shot into the recess in the steering- 25 head, said bolt having a cap or guard at its outer end of such size as to prevent access to the heads of the carrier-holding screws, thereby thwarting the removal of the lock from the steering-head tube of the bicycle by un- 30 authorized persons.

In the drawings accompanying and forming part of this specification, Figure 1 is a side elevation of the front part of a bicycle, showing my improved lock on the steering-head. Fig. 2 is a sectional side elevation of the steering-head, its tube, and the lock, on an enlarged scale, the bolt being illustrated in its protracted or working position to lock the steering-head against turning. Fig. 3 is 35 a substantially similar view, the bolt being represented in its retracted position. Fig. 4 is a sectional plan view, the section being taken through the steering-head and steering-head tube in a line slightly above the lock in 40 Fig. 2. Fig. 5 is a horizontal central section of the lock. Fig. 6 is a transverse section taken in a line passing through the center of the lock-cylinder, and Fig. 7 is an elevation of a simple form of key for actuating the 45 lock.

Similar characters designate like parts in all the figures of the drawings.

The steering-head tube of the bicycle is designated by T and the steering-head by S, and both of these may be of any suitable or 55 usual type.

The steering-head tube in the present case carries the lock proper, which is designated by L, and the steering-head forms a keeper for the lock-bolt, said steering-head having a 60 plurality of bolt-receiving recesses, as 2 and 3, into either one of which the inner end of the lock-bolt may be inserted to secure the head to the steering-head tube, so as to prevent the head from turning. 65

My improved lock embodies as a part thereof a bolt-carrier, which may be secured to the steering-head in any suitable manner, but which is preferably fixed thereto by holding-screws, as 4 and 5, respectively, in threaded 70 engagement with the steering-head tube T and passing through openings near the inner end of the carrier, (designated by H,) that portion of the latter which fits against the steering-head being of a shape to correspond 75 with said head.

The lock-bolt carrier H has in diametrically opposite sides thereof the grooves or channels 6 and 7, respectively, to admit a suitable instrument for driving the two screws 4 and 5, 80 respectively, into their seats in the tube T when the lock is placed on a machine.

The bolt-lock is designated by B, and it is longitudinally reciprocative in the bore 8, extending entirely through the carrier, the inner end of said bolt being adapted to be projected into one or the other of the recesses 85 2 and 3 in the steering-head S, and also passing through an opening or slot 9 in the tube T.

The bolt-carrier H is surrounded by the 90 casing or collar 10, which, when the parts are assembled, is adapted to fit against the abutment or shoulder 12 near the inner end of said bolt-carrier.

The outer end of the bolt B is provided 95 with a cap or guard which serves to prevent access to the heads of the carrier-holding screws 4 and 5 when the parts are assembled in working position on the machine. This cap or guard is designated by 13, and it consists in 100 the present case of a disk which may be formed integral with the bolt B, and its diameter is approximately equal to that of the casing or sleeve 10, and it will be apparent on an in-

specion of the drawings that when the lock parts are assembled it is impossible to introduce a screw-driver or other tool in the grooves 6 and 7 for the purpose of removing the screws.

5 The bolt-lock B is preferably thrown into or out of the steering-head recesses 2 and 3 by a key-operated cylinder, as C, situated for rotation in a transverse opening 14 in the bolt-carrier II, and said cylinder is connected 10 with the bolt by a joint eccentric to the axis of rotation of the cylinder, so that when the cylinder is manipulated by a key the bolt may be shot into or out of the keeper-recesses in the steering-head in accordance with the direction in which said cylinder may be turned.

15 The lock-operating cylinder C consists in the present case of two superposed parts 15 and 16, respectively, independently rotative and secured to each other by the pivot 17, 20 consisting of a rivet whose lower end may be headed to prevent the separation of the two cylinder parts. The cylinder passes through the recess 18 in the casing 10, and it is constructed, preferably, of different sizes, the 25 under section 15 being of greater diameter than the upper, by reason of which a stop or shoulder 19 is produced near the middle of the cylinder and bears against the sleeve 10 to prevent the removal of the said cylinder.

30 The two parts of the cylinder C are longitudinally grooved or notched in their opposite sides, as at 20 and 21, respectively, and when the notches of the upper section are in alinement or registration with the corresponding notches on the under cylinder-section it will be evident that the cylinder may be turned by a key, such as K, adapted to straddle the cylinder, the bits or branches 22 and 23 of which are adapted to enter the alined 35 notches or grooves in the opposite sides of the cylinders.

40 The under cylinder-section 15 is equipped with a depending stud or pin eccentric to the axis of rotation of the cylinder, which is adapted to enter the peripheral socket 26' in the lock-bolt B, and by virtue of the connection just described it will be apparent that when the cylinder is turned in the manner previously indicated the lock-bolt will be 45 thrown into or out of one of the recesses in the steering-head to lock or unlock the latter.

50 The tumbler for locking the bolt in its respective positions may be of any suitable construction. The tumbler in the present case 55 consists of a longitudinal curved spring 25, seated in the channel 26 of the bolt-carrier II, the groove being deepest at a point adjacent the cylinder, thereby to permit the working or free end of the spring to be sunk into 60 said recess to release the cylinder. The opposite end of said spring is secured to the carrier in some convenient manner. The spring-tumbler 25 is held in a notch of the casing 10.

65 The free or working end of the spring is adapted to enter either one of the notches 20 and 21 in the lower cylinder-section 15, thereby to lock the bolt in either one of its two po-

sitions, and these parts are maintained in effective engagement by the collar 10, which holds the spring in a notch. The free end of 70 the spring is disposed in the path of one of the bits 22 and 23 of the key K, and when the bit strikes the spring the latter is thrust out of the notch in which it had been seated, so that 75 the cylinder is released and can be turned by the key, and when the bolt reaches its other extreme position the free end of the spring will enter the opposite notch on the cylinder when the key is withdrawn to hold the lock-bolt.

80 To attach the lock to a cycle, the carrier II is first placed against the tube T with its bolt-receiving bore 8 in alinement with the opening 9 in the tube, after which the holding-screws 2 and 5 are inserted into their openings in the carrier and turned into the tube T by a screw-driver or other tool. The casing or ring 10 is then placed over the bolt until the inner end of the ring abuts against the inside face of the disk or guard 13. Then the ring is placed over the carrier until the socket 26' in the bolt B is visible through the aperture 14, at which time the cylinder is inserted into the said aperture and the eccentric pin thereon will drop into the pocket. The spring 25 is then lowered below the inside face of the ring 10, so that the latter can be pressed against the shoulder 12 on the bolt-carrier II. When the ring has reached the head or shoulder 12 of the carrier, it serves to press the working end of the spring 26 into one of the notches of the bolt-operating cylinder C to lock the latter and consequently the bolt B, the release of the bolt being effected by forcing the spring-tumbler out of the notch by a key-bit.

Having described my invention, I claim—

1. The combination with a bicycle-frame embodying a steering-head and a tube thereon, of a carrier having screw-receiving openings; a series of screws passing through said openings and in threaded engagement with the steering-head tube, a casing fitting around the carrier outside of the screw-receiving openings to laterally guard the screws, a bolt 110 passing through a bore of the carrier and adapted to be projected into an opening in the steering-head, and means serving to prevent access to the heads of the carrier-holding screws.

115 2. The combination, with a bicycle-frame embodying a steering-head and a tube thereon, of a carrier having screw-receiving openings; a series of screws passing through said openings and in threaded engagement with the steering-head tube; a casing fitting around the carrier outside of the screw-receiving openings to laterally guard the screws; a bolt passing through a bore in the carrier and adapted to be projected into an opening in the 120 steering-head, said bolt having a cap or guard at its outer end constructed to prevent access to the heads of the carrier-holding screws.

125 3. The combination, with a bicycle-frame

embodying a steering-head and a tube thereon, of a carrier having screw-receiving openings; a series of screws passing through said openings and in threaded engagement with the steering-head tube; a casing fitting around the carrier outside of the screw-receiving openings to laterally guard the screws; a bolt passing through a bore in the carrier and adapted to be projected into an opening in the steering-head, said bolt having a disk at its outer end, which serves to prevent access to the heads of the carrier-holding screws.

4. The combination with a bicycle-frame embodying a steering-head and a tube thereon, of a substantially cylindrical carrier having screw-receiving openings and diametrically opposite screw-receiving channels com-

municating with said openings, a series of screws passing through said openings and in threaded engagement with the steering-head tube, a casing fitting around the carrier outside of the screw-receiving openings to laterally guard the screws, a bolt passing through a bore in the carrier and adapted to be projected into an opening in the steering-head, means serving to prevent access to the carrier-holding screws, and a bolt-operating cylinder adapted to be passed through a slot in the casing.
